UNITED STATES PATENT OFFICE.

EMIL LEESER, OF CHICAGO, ILLINOIS.

MANIFOLDING DEVICE.

SPECIFICATION forming part of Letters Patent No. 717,691, dated January 6, 1903.

Application filed March 4, 1902. Serial No. 96,706. (No model.)

To all whom it may concern:

Be it known that I, EMIL LEESER, a citizen of the United States, residing at Chicago, in the county of Cook and State of Illinois, have 5 invented certain new and useful Improvements in Manifolding Devices, of which the following is a specification.

This invention relates to improvements in manifolding devices used more especially for 10 keeping copies of bills and the like in suitable books for this purpose. Its objects are to provide means for conveniently holding the carbon - sheet in close proximity to the leaf of the blank book, means for furnishing 15 a suitable binder or holder for the carbon, means for holding any number of blank bill-heads or statements to be filled out, means whereby the holding devices may be raised to allow a leaf of the book to be readily turned, 20 and adjustable means for securing the holding devices to enable its use with books of various sizes.

It consists in the various combinations and novel features, which will be described and 25 claimed hereinafter and is illustrated in the accompanying drawings, in which—

Figure 1 is a perspective view of the holding device as secured to a book and also shown in dotted lines in raised position to enable the leaves of the book to be turned. 30 Fig. 2 is a plan view of the holding device detached from the book and showing the carbon-paper binder in position. Figs. 3 and 4 are views of the combined clip and carbon- 35 paper holder. Fig. 5 is a detail showing the clip for engaging the book-cover. Fig. 6 is a detail showing the carbon - paper binder. Fig. 7 is a detail showing a modified form of rail or rod for the clip to engage with.

Any suitable blank book may be used with this device and may be represented, as shown in the drawings, by 1. A guide rod or tube 2 is adapted to be held substantially in the crease formed by the back binding. This is 40 preferably made with extensions or arms 3, extending at right angles thereto and pivoted at 4 to clips or clamps 5, which engage the cover 6 at points about midway of its width. By means of this novel method of attachment 45 the rod or tube 2, with any attachments secured thereto, may be readily raised, as shown in dotted position in Fig. 1, to allow

a leaf of the book to be turned. As shown in Figs. 2 and 5, the clip 5 is formed by stamping out of sheet metal and the fingers 7 struck 55 up to allow the necessary opening for the book-cover. The pivoted arms 3 are bent at right angles to form stems 8, which extend into the tube 2 and are prevented from being disconnected by pins 9 at the ends thereof, 60 which slide in a slot 10 in the tube 2 and engage with bands 11 at the ends of said tube. By means of this arrangement the clips 5 may be separated to span the book-cover and then pressed toward each other to engage it. 65 This will also allow a limited adjustment for books of various sizes. The combined bill-head and carbon-paper clamp and holder 12 is slidably secured to the slotted tubular guide 2 by a cylindrical head 13, which engages said guide, as shown. The clamp 12 is of the usual form of construction of spring-clamps; but the upper jaw is provided with a rubber facing 14, and the lower jaw is provided with clips 15 to hold the carbon or 70 copying paper or a holder for the same. By means of these auxiliary clips the bills may be readily removed without disturbing the carbon-paper, which may be used until worn out. The lower jaw of the clamp 12 is also 75 turned up at the back, as at 16 16, to form a guide or straight edge against which the bill-heads may be pressed to hold them in alignment and proper position.

The carbon or copying paper is preferably 80 secured in a holder or binder 17, which is plainly shown in Fig. 6. This is made of any suitable material, such as leather, and is provided at the corners with buttons or fasteners 18, which hold the paper in place. It is preferably left open at the bottom to admit using any size sheets of paper.

A modified form of guide-rod is shown in Fig. 7. This consists of a grooved rod 19, and the clamp 12 is provided with a suitable head 95 to engage the same, as shown.

The operation of this device is as follows: The book is opened and the clips 5 pressed onto the cover, as shown, with the guide-rod 2 in the center of the book. The binder 17 100 with its sheet of carbon-paper is then placed in the clips 15 and one or more bill-heads placed in the clamp 12. If more than one bill-head is placed in the clamp, all but the

last one are raised and that one is filled out, leaving a copy of the writing on the leaf of the blank book. It is then removed, the clamp moved down, and the next filled out, 5 and this continued until the page is filled. A scale 20 on the guide 2 enables the operator to properly adjust the clamp each time. When the page is filled, the rod 2 is raised, as hereinbefore described, a leaf of the book 10 turned, and the process continued.

I am aware that various minor changes and modifications, such as means for securing the clamp to its guide-rod and making the rod adjustable, will readily suggest themselves as 15 coming within the scope of this invention, which I do not wish to limit to the exact construction shown; but

What I claim, and desire to secure by Letters Patent, is—

20 1. In a manifolding device the combination of a book, clips engaging the cover of said book, arms pivoted to said clips, a guide-rod

adjustably secured to said arms, and a clamp slidably secured to said guide-rod.

2. In combination, a book, clips engaging 25 the cover of said book, arms pivotally secured to said clips, a slotted tubular guide adjustably secured to said arms, a clamp provided with a cylindrical head engaging said tubular guide and having auxiliary clips for holding 30 a carbon-sheet.

3. In combination, a blank book, clamps for engaging the cover of said book, arms pivotally connected to said clamps, an adjustable guide-rod carried by said arms, a clamp 35 slidably secured to said rod, a guide on said clamp, auxiliary clips on said clamp, a carbon or copying paper holder engaging said clips and provided with fasteners to hold the carbon-paper substantially as described.

EMIL LEESEER.
